CLAIM

The ornamental design for a connector, as shown and described.

DESCRIPTION

FIG. 1 is a front, top, and side perspective view of an embodiment of a connector.

FIG. 2 is a back, top, and side perspective view thereof.

FIG. 3 is a top view thereof, the bottom being a mirror image.

FIG. 4 is a side view thereof, the opposite side being a mirror image.

FIG. 5 is a front view thereof; and,

FIG. 6 is a back view thereof.

The broken lines in the drawings illustrate portions of the connector that form no part of the claimed design.
